MANTILLA OR THE LIKE

Lillian Gettinger, 2509 Shelley Dale Drive,
Baltimore, Md.

Filed Oct. 7, 1963, Ser. No. 76,881

Term of patent 14 years

(Cl. D3—13)

FIG 1

FIGURE 4 is an enlarged fragmentary plan view illustrating in detail the connection between the hood portion of the mantilla and one of the depending portions thereof.

I claim:

The ornamental design for a mantilla or the like, as shown.
